Primary Examiner — Eric Goodman*Assistant Examiner* — Sloan Rozin(74) Attorney, Agent, or Firm — NSIP Law(57) CLAIM

The ornamental design for a display screen or portion thereof with icon, as shown and described.

DESCRIPTION

FIG. 1 is a front view of a display screen or portion thereof with icon showing our new design; and,

FIG. 2 is a front view of a second embodiment thereof.

The long dash, dot broken lines shown in FIGS. 1 and 2 represent the display screen or portion thereof and form no part of the claimed design.
